UNITED STATES PATENT OFFICE.

JAMES HARVEY STRONG, OF STEUBENVILLE, OHIO.

DESIGN FOR A SHADE-BOWL.

42,718.

Specification for Design.

Patented July 2, 1912.

Application filed April 23, 1912. Serial No. 692,720. Term of patent 7 years.

To all whom it may concern:

Be it known that I, JAMES HARVEY STRONG, a citizen of the United States of America, and a resident of Steubenville, in the State of Ohio, have invented a certain new, original, and ornamental Design for a Shade-Bowl, of which the following is a specification.

The figure is a perspective view of the bowl or shade in upright position.

The shade consists of a depending bowl with a flaring edge as shown inscribed with a Grecian border "1," of the type known as the wall of Troy, encircling the periphery "2" of the bowl, and having an acorn knob "3" at the lower end of its axis. Adjacent

the knob around the lower end of the axis is a leaf design "4," and radiating from this design are meridional flutes "5" separated by ridges "6," the ridges and flutes disappearing in the neighborhood of the border.

I claim:

The ornamental design for a shade bowl as herein described and shown.

Signed by me at Steubenville in the State of Ohio this 20 day of April, 1912.

JAMES HARVEY STRONG.

Witnesses:

HENRY F. WILLIAMS,
E. WEHMEYER.
